UNITED STATES PATENT OFFICE.

JUSTUS HATTEMER, OF WEST NEW YORK, NEW JERSEY, ASSIGNOR TO HARDMAN,
PECK & COMPANY, OF NEW YORK, N. Y., A CORPORATION OF NEW YORK.

PEDAL.

1,110,202.

Specification of Letters Patent.

Patented Sept. 8, 1914.

Application filed April 18, 1913. Serial No. 762,044.

To all whom it may concern:

Be it known that I, JUSTUS HATTEMER, a citizen of the United States, residing at West New York, in the county of Hudson and State of New Jersey, have invented certain new and useful Improvements in Pedals; and I do hereby declare the following to be a full, clear, and exact description of the invention, such as will enable others skilled in the art to which it appertains to make and use the same.

This invention relates to pedals for player grand pianos and has for an object to provide a pedal operably associated with a lyre of substantially the usual and ordinary form and movable to obscurity leaving comparatively no evidence of its existence behind upon the lyre.

A further object of the invention is to provide a pedal structure vertically slidable relative to a lyre with means for maintaining the pedal structure in both raised and lowered position, the lowered position being the operative position, and the raised position being the inoperative position.

A further object of the invention is to provide guides associated with a lyre upon which a pedal structure slides vertically, with means for counterbalancing the pedal both in raised and lowered positions.

A further object of the invention is to provide improved means for locking the pedal structure in lowered or operative position.

A further object of the invention is to provide improved means for attaching the pedal to the wind apparatus by means of a stirrup and flexible strap with means for tilting the stirrup in a predetermined direction when the pedal is raised.

A further object of the invention is to provide improved winding means for attaching cables controlling the pedals and counterweight.

With these and other objects in view the invention comprises certain novel constructions, combinations and arrangement of parts as will be hereinafter more fully described and claimed.

In the drawings: Figure 1 is a view of the improved pedal in side elevation shown in full lines in lowered or operative position and in dotted lines at raised and an intermediate position. Fig. 2 is a view of the pedal structure and lyre in front elevation. Fig.

3 is a view of the pedal structure and lyre in rear elevation. Fig. 4 is a transverse sectional view taken on the horizontal plane as at line 4—4 of Figs. 1, 2 and 3. Fig. 5 is a top plan view of the structure and operating means. Fig. 6 is a view of the pedal structure attached to a player grand piano. Fig. 7 is a sectional view through the winding drum taken on line 7—7 of Fig. 5. Fig. 8 is an enlarged view in side elevation of the sliding block and lock. Fig. 9 is a sectional view of the guiding block. Fig. 10 is a top plan view of the sliding block as indicated by arrow 10 of Figs. 8 and 9. Fig. 11 is a detail view of the latch operating and lifting mechanism.

Like characters of reference designate corresponding parts throughout the several views.

It is well known that in player pianos it is necessary to provide auxiliary pedals for operating the player mechanism and that it is considered necessary or desirable to move the auxiliary pedals out of sight for use of the piano as a manual piano. It is also well known that in player grands the removal of the pedals from sight has proved to be a troublesome feature and that lyres of various cabinet formation have been provided into which the pedals have been folded.

The present invention embodies a lyre of substantially the usual and ordinary form, the lyre illustrated in the drawings being shown conventionally it being understood that any ordinary form of lyre may be substituted therefor.

Along the sides of the lyre guide rods 16 are erected secured to the base of the lyre by a cross bar 17 or its equivalent as shown at Fig. 3 of short bar members rigidly secured to the under side of said base. The tops of the rods are secured in any approved manner as by means of clips 17' shown at Figs. 1 and 5.

Slidable upon these guide rods 16 are blocks 18 carrying rigidly connected thereto arms 19 which together with the cross bar 20 rigidly carried thereby form the pedal supporting frame. The blocks 18 are provided with rollers 21 as shown at Figs. 4, 9 and 10 which rollers are grooved to embrace the guide rods 16 and are journaled within the blocks 18.

To lock the pedal supporting frame in lowered position the blocks 18 are provided

with latches 22 pivoted thereto as at 23 shown particularly at Fig. 8 and held yieldingly in position to engage the cross pieces 17 by springs 24. The latches 22 are retracted by means of rods 25 pivoted to such latches and controlled by means of a lifting member 26 to which they are pivotally secured by means of the slot and keeper indicated at 27 especially in Fig. 11. It will, therefore, be apparent that when the end of the lifting member is lifted as indicated by the arrow at Figs. 1, 6 and 11 the said member will be moved upon its pivot 28 as shown at Fig. 11 to release the latches 22. 15 Also to assist in such lifting a counterweight 29 is provided slidable upon guide rods 30 which terminate and are secured at their lower ends in a cavity, recess or box 31 formed in the rear of the base of the lyre, the recess and its addition to contain the same being shown at Figs. 1, 4 and 6. The counterweight is supported by a cable 32 passed over a pulley 33 and about a winding drum 34. The winding drum as will be seen more particularly from Figs. 2 20 and 7 is provided with three grooves, the lower one of which 34' accommodates the cable 32 and the others 35 and 36 accommodate respectively cables 37 and 38 which are connected with the arms of the sliding blocks 18, as shown particularly at Figs. 1 and 6. The cables 37 and 38 pass respectively over pulleys 39 and 40 by which the direction is changed to wind about the 25 drum 34.

It will, therefore, be seen that the counterweight 29 sliding upon its rods 30 serves to counterbalance the pedal supporting structure. The pedal supporting structure carries mounted thereon pedals 41 and 42 pivoted in any approved manner at the heel end as by pivots 43 whereby the pedals may be actuated by the foot of the user in substantially the usual and ordinary manner. 40 The pedals are provided with stirrups 44 to which straps 45 are connected extending upwardly to the wind apparatus to which it is connected in any suitable manner, not shown. Attached to the lower end of the strap by any approved form of clamp or buckle 46 is a loop 46' which loosely embraces the bend of the stirrup. Secured beneath the pedal is a spring 47 whose free end passes the edge of the pedal and presses 45 forward behind the stirrup 44. As seen in the first dotted position in Fig. 1, when the pedal begins to rise and tension on the strap is reduced, the stirrup is tilted as also indicated at that position to insure its lying upon the pedal in proper relation as shown in the upper dotted position of Fig. 1, the strap 45 also folding down upon the top of the pedal when raised.

Oblique braces 48 are rigidly secured to 50 the cross bar 20 and to the arms 19 adja-

cent the blocks 18 which prevent any twisting action of the pedal supporting structure. A brace shown as a whole at 49 is also provided hinged to the lyre as indicated at 50 whereby it may be raised as seen in dotted lines in Fig. 1 and held raised by a keeper 51. The latter may be a hook or catch of any suitable form, but in Fig. 2 I have shown it as comprising two spring jaws between which the brace is forced when raised. 70

The brace 49 is bifurcated at its lower end and such extremities are provided with adjustable points in the form of nuts 52 engaging sockets 53 as shown more particularly at Figs. 1 and 11. The brace 49 may be moved upwardly or downwardly as indicated in its two positions at Fig. 1 and when down its points rest in the bottom of the sockets 53 to hold the pedal supporting structure firmly in its downward position, the tension required being secured by adjusting said points 52. When the pedal is to be raised the brace 49 is first raised to the highest dotted line position in Fig. 1 and retained in such upward position by engaging said brace behind the keeper 51 whereupon the pedal structure is free to rise as an entirety as indicated by the two dotted positions in Fig. 1. Adjacent their upper ends the guide rods 16 are provided with rearwardly deflected portions 54 by the use of which the pedal supporting frame is raised from an inclined position as shown in full lines at Fig. 1 to a horizontal position as shown in dotted lines in such figure whereby the pedals are obscured under and behind the downwardly projecting flange 55 of the piano body. As shown at the various figures the regular piano 105 pedals 56, 57 and 58 are employed upon the lyre actuating respectively rods 59, 60 and 61 which form no part of the present invention except as they work in harmony with the auxiliary pedal structure disclosed 110 thereby.

I claim—

1. The combination with a piano player, of pedals slideable vertically relative thereto, means to latch the pedals in lowered position, and means whereby to manually lift the pedals, said lifting means unlatching the latching means. 115

2. The combination with a piano; of guides disposed beneath the piano and vertical for the major portion of their length but having their upper portions deflected to the rear, blocks slideable upon the guides and their deflected portions, and a pedal supporting structure carried by the blocks. 120

3. The combination with a piano, of guides extending downwardly therefrom, a cross bar connecting the lower extremities of the guides, a pedal supporting structure slideable upon the guides, a latch carried by 130

the supporting structure capable of engaging under the cross bar, a manual lever pivoted upon the pedal supporting structure, and means connecting the manual lever with the latch.

4. The combination with a piano, of guides extending downwardly therefrom, a pedal supporting structure slideable upon some of said guides, a counter weight slideable upon other of said guides and cables connected to the supporting structure and the counterweight whereby the counterweight counterbalances the supporting structure.

15 5. The combination with a piano, of guides extending downwardly therefrom, a winding drum adjacent the tops of the guides, a pedal supporting structure slideable upon some of said guides, cables extending from said supporting structure to the drum, a counterweight slideable upon others of said guides, and a cable extending from the counterweight to said drum.

6. The combination with a piano embodying a body and means to support the body spaced above the floor, of a lyre extending down from the body adjacent the floor; guides extending vertically from the base of the lyre upwardly toward the body

and bent at an angle where they join with the body; blocks slideable upon the guides and adapted to be changed from a vertical to an inclination as they pass the bend of the guides; and a pedal supporting structure carried by the blocks.

7. The combination with a piano embodying a body and means to support the body spaced above the floor, of a lyre extending down from the base of the lyre upwardly and deflected to the rear where they join with the body; blocks slideable upon the guides and adapted to be changed from a vertical to an inclination as they pass the bend of the guides, a pedal-supporting structure carried by the blocks, other guides extending from said body straight downward, a counterweight slideable upon these guides, and a cable connecting said counterweight and blocks and passing intermediate its ends over a pulley.

In testimony whereof I affix my signature in presence of two witnesses.

JUSTUS HATTEMER.
